UNITED STATES PATENT OFFICE.

JOHN GRIME, OF MINNEAPOLIS, MINNESOTA, ASSIGNOR OF ONE-HALF TO
GEORGE H. EASTMAN, OF SAME PLACE.

VALVE-GEAR FOR ENGINES.

SPECIFICATION forming part of Letters Patent No. 351,912, dated November 2, 1886.

Application filed July 31, 1886. Serial No. 209,618. (No model.)

To all whom it may concern:

Be it known that I, JOHN GRIME, a citizen of the United States, residing at Minneapolis, in the county of Hennepin and State of Minnesota, have invented certain new and useful Improvements in Valve-Gear for Engines, of which the following is a specification.

My invention relates to mechanism for operating the valves of steam-engines.

10 The object of my improvements is to secure an equal valve-movement and a uniform cut-off and exhaust for both the backward and forward throws of the valves; and my invention relates particularly to improvements upon the 15 valve-gear described in Letters Patent granted me on November 17, 1885, No. 330,782, and February 9, 1886, No. 335,578.

My improvements are illustrated in the accompanying drawings, in which Figure 1 represents a driving-wheel and a portion of a locomotive provided with my improvements. Fig. 2 is a side view in detail of the parts connected to the boiler and driver-axle for supporting and operating the valve-rods. Fig. 3 is a front view 25 of the same. Figs. 4 to 9, inclusive, are details of parts of the same, which will be hereinafter more fully described; and Fig. 10 illustrates my improvements in connection with a horizontal engine made to operate automatically by means of a governor and eccentric.

In the drawings, A represents the locomotive-boiler; B, one of the driving-wheels, and a the driver-axle.

C is a rock-shaft operated from the engine-cab by levers in the usual manner, and it is mounted on a standard, D, which is boxed on the axle a.

c is a guide carried on the end of the rock-shaft C, and d is a slide-block operating in and 40 controlled by the guide c. The standard D is prevented from turning, while it is allowed vertical movement corresponding with the up-and-down movement of the axle a by means of brackets e, bearing guides e', which are adjustable by means of set-screws e''. The brackets may be secured to the lower side of the boiler; or, if desired, they may be supported by the engine-frame. The middle portion of the standard D may be divided and a bar, d', 45 passed between the parts and secured to the

lower end of the brackets e, thus making the brackets firm and preventing the standards from sliding on the axle a. The brackets prevent lateral movement of the rock-shaft and parts connected to it, while permitting them 55 to follow the up-and-down movements of the driver-axle occasioned by unevenness of the road-bed.

D' is a slide-block furnishing a bearing for the rock-shaft C, and the block is permitted 60 vertical movement in the side walls, d'', of the standard D.

f f' are blocks secured on the standard adjacent to the guide c. The upper surface of the block f and the lower surface of the block f' 65 are double curved in corresponding courses, and are separated at suitable distance to form a curved way, w, for a roller-wheel.

o is the roller-wheel, having one end of its axle in a bearing, h, in the guide c, and the 70 other in a bearing, i, in a casting, k. The casting or piece K (shown in detail in Figs. 7 and 8) is secured by screws through holes k' in its upper portion to the upper portion of the guide c, and it has a central opening, k'', through 75 which the rock-shaft passes.

It will be obvious that when the rock-shaft is partially rotated by shifting the usual lever in the locomotive-cab the rock-shaft and the guide c, which it carries, will be slightly elevated or depressed, depending on the curvature of the way w, in which the roller o is thus made to travel, and that the changed inclination of the guide c will slightly affect the throw of the valves. If the guide c is held on a fixed 80 axis and its inclination is changed by turning that axis, the effect is to vary the valve-throw and make a slight inequality in the cut-off and exhaust of the respective strokes; but by

suitably raising or lowering the guide c, as its 85 inclination is changed the inequality of valve-movement referred to may be obviated. So, by providing the way w, of suitably-curved form relatively to the operations and proportions of other parts of the valve-gear, the guide c will 90 be raised or lowered sufficiently to compensate for any irregularity in the valve-movements which would otherwise be occasioned by a 95 change of the guide inclination, and thus a uniform cut-off and exhaust are secured for 100

both forward and backward throws of the valves.

In Fig. 10 is illustrated a stationary engine provided with my improvements above described, and in which the rock-shaft is operated by means of an eccentric and a governor, to render the engine automatic.

m is a governor of ordinary construction, and supported in any suitable manner. To the sliding sleeve *n* on the governor-spindle is connected an arm, *p*, whose opposite end is attached to the face of the eccentric *s*, by means of which the eccentric is partially rotated as the sleeve is raised or lowered by the action of the governor. To the strap *t* of the eccentric is attached a rod, *v*, which is connected to the lever *x* for operating the rock-shaft.

The other parts of the mechanism are substantially the same in construction and operation as the corresponding parts heretofore described.

Having fully described my invention, what I claim, and desire to secure by Letters Patent, is—

1. In combination, in a valve-gear, a rock-shaft, a guide and slide-block carried thereby, a shaft, an eccentric thereon connected to said slide-block, a standard boxed on said shaft, a curved way provided in said standard, and a roller-wheel in said way for raising or lowering said rock-shaft, substantially as set forth.

2. In combination, in a valve-gear, a rock-shaft, a guide and slide-block carried thereon, a shaft, a standard boxed thereon and provided with a sliding bearing for said rock-shaft, a curved way for a roller provided on said standard, and roller therein having one of its bearings in said guide and the other in a casting attached thereto, substantially as and for the purpose set forth.

3. In a valve-gear, the combination, with a rock-shaft carrying a guide and slide-block, of a standard boxed on the main axle, a curved way therein, and a roller in said way operated by said rock-shaft, substantially as and for the purpose set forth.

4. In a valve-gear, the combination, with a guide carried by a rock-shaft and a slide operated by an eccentric on the main shaft, of the blocks *f* and *f'*, forming the way *w*, and the roller-wheel *o*, substantially as set forth.

5. The combination, with a valve-gear, substantially the construction shown and described, of a governor, an eccentric operated by said governor, and a rod connecting said eccentric with the rock-shaft levers, substantially as set forth.

JOHN GRIME.
